DESIGN FOR A PARACHUTE PACK

Floyd Smith, Manchester, Conn., assignor to Pioneer Parachute Company, Inc., Manchester, Conn., a corporation of New Jersey

Application December 8, 1939, Serial No. 88,767

Term of patent 14 years

To all whom it may concern:

Be it known that I, Floyd Smith, a citizen of the United States, residing at Manchester, in the county of Hartford and State of Connecticut, have invented a new, original, and ornamental Design for a Parachute Pack, of which the following is a specification, reference being had to the accompanying drawing, forming a part thereof.

Fig. 1 is a front elevational view of a parachute pack embodying my new design.

Fig. 2 is a rear elevational view of the parachute pack illustrated in Fig. 1.

Fig. 3 is a side elevational view of the parachute pack illustrated in Fig. 1.

Fig. 4 is a top plan view of the parachute pack illustrated in Fig. 1, and

Fig. 5 is a view from the bottom looking upward on the parachute pack illustrated in Fig. 1.

The characteristic feature of the design for a parachute pack of the present invention resides in the upper portion including a head rest and in its relation to and association with the lower body portion of the pack.

I claim:

The ornamental design for a parachute pack, substantially as shown and described.

FLOYD SMITH.
